UNITED STATES PATENT OFFICE

JULIUS L. DE GIVE, OF ATLANTA, GEORGIA; HENRY L. DE GIVE EXECUTOR OF SAID
JULIUS L. DE GIVE, DECEASED

MAIL BAG

Application filed November 8, 1929. Serial No. 405,756.

This invention relates to mail bags especially designed for air mail, an object being to provide a bag which will be fire-proof, water-proof and non-sinkable, so that the contents of the bag will be preserved in the event of an accident to the carrying plane resulting from fire, or other causes, while the bag and its contents may be recovered should such accident occur over water.

With the above and other objects in view, the invention further includes the following novel features and details of construction, to be hereinafter more fully described, illustrated in the accompanying drawings and pointed out in the appended claims.

In the drawings:—

Figure 1 is an elevation of a mail bag constructed in accordance with the invention, parts being broken away to more clearly illustrate the bag structure.

Figure 2 is a similar view illustrating the means for preventing the bag from sinking.

Figure 3 is a plan view of Figure 2.

Figure 4 is an enlarged fragmentary sectional view on the line 4—4 of Figure 1.

Figures 5 and 6 are sectional views showing different forms of buoyant members.

Figure 7 is an elevation of the inner water-proof bag.

Figure 8 is a top view of the same.

Figure 9 is an enlarged fragmentary sectional view taken substantially on the line 9—9 of Figure 7.

Figure 10 is a fragmentary elevation showing a different means for holding the water-proof bag closed.

Figure 11 is an edge view of the subject matter of Figure 10.

Figure 12 is a plan view showing another means for closing the bag.

Figure 13 is an enlarged fragmentary

sectional view taken substantially on the line 13—13 of Figure 12.

Referring to the drawings in detail wherein like characters of reference denote corresponding parts, the reference character 10 indicates a mail bag which is made of fire-proof material, so that the bag may be used for air mail and the contents preserved in the event of accident by fire. The bag is further water-proof so that the contents of the bag will also be protected from the action of water should accident occur when the plane is flying over a body of water. For this purpose, the bag is constructed of an outer fire-proof bag and an inner water-proof bag. The material for the outer bag may consist of asbestos cloth such as is used for fire-proof curtains in theaters. This cloth usually consists of asbestos having its threads or strands woven upon copper wire. A bag of this character would not only be fire proof, but of great strength due to the wire reinforcement.

The open end of the outer bag 10 is preferably provided with a flap 11 extending from one edge, this flap is turned down over the opposite edge of the bag. Eyes or staples 12 extending from this last referred to edge pass through grommets or eyelets 13, while a rod or stiff wire cable 14 is passed through the eyes or staples 12 and is secured in place by means of a lock 15. If desired, a flexible cable or draw string may be passed directly through the grommets, in this case both sides of the bag would be of the same length with no flap on the bags.

The bag may also be provided with an eye 16, the shank 17 of which is secured to the bag, so that the said bag may be supported upon a rod or other suitable device arranged beneath the bottom or upon opposite sides of the carrying plane. Also, due to the flexibility of the bag structure, the latter may be folded so as to occupy a rela-

tively small space in the event that the bag is not entirely filled with mail matter.

For the purpose of rendering the bag non-sinkable, a flexible member 18 extends around the bag preferably near each end thereof. This member is threaded through suitable eyelets 19 and carries a plurality of buoyant elements 20. These elements may consist of cork or balsa wood, or they 10 may be hollow copper elements having openings therethrough for the passage of the flexible member. While the buoyant elements are shown at opposite ends of the bag, their number and arrangement may 15 vary in accordance with the weight of the contents of the bag. The buoyant elements however are preferably arranged so that the bag will float mouth upward.

In Figure 5 a spherical copper or other 20 metallic element 21 is illustrated, a similar element 22 of substantially oval-shape is shown in Figure 6.

The inner bag which is indicated at 21^a 25 may be made of any suitable material, such as oiled canvas, silk, or rubber coat fabric of the character used in the manufacture of raincoats.

The bag 21^a is folded a suitable number 30 of times as indicated at 22^a so as to prevent the entrance of water into the bag. Means are provided for holding the bag closed, and in Figures 7, 8, and 9, this means consists of a pair of clamping strips 23 whose adjacent ends are connected by bolts 24 and thumbnuts 25. The folded mouth of the bag may thus be tightly and securely closed and inserted within the outer fireproof bag 10. By making the bags 10 and 21^a separate, and by providing separate closing 35 means for each of the bags, the inner waterproof bag may be securely closed before being placed within the outer fire-proof bag so that danger of leakage in through the mouth of the bag 21^a will be prevented.

40 In Figures 10 and 11, a spring influenced clamp 26 is substituted for the closing means shown in Figures 7, 8, and 9.

In Figures 12 and 13, the mouth of the bag is closed by the well known slidable 45 closure as indicated at 27.

The invention is susceptible of various 50 changes in its form, proportions and minor details of construction and the right is herein reserved to make such changes as properly fall within the scope of the appended claims.

Having described the invention what is claimed is:

60 1. The combination with a mail bag, of flexible cable members extending around the bag near the top and bottom ends thereof, spaced eyelets disposed around the bag adjacent the opposite ends of the bag and through which the cable is threaded, and 65 buoyant elements carried by each cable and

disposed between the confronting portions of each of the eyelets.

2. The combination with a mail bag, of 70 flexible cable members extending around the bag, spacing means for attaching the cable members to the bag, buoyant elements carried by each cable member and disposed between the confronting portions of each of the spacing means, and a closure for said bag.

75 In testimony whereof I affix my signature.

JULIUS L. DE GIVE.
